SETTING FOR PRECIOUS STONES

Lee Hirsch, New York, N. Y.

Application November 10, 1938, Serial No. 239,798

14 Claims. (Cl. 63—26)

The invention relates to settings for precious stones and particularly to settings for diamonds. It has especial application to rings, although it is useful in the construction of other articles of jewelry as well. It will be described with more particular reference to wedding rings and similar rings in which a number of diamonds or other stones are set in a row or series.

In the art of diamond setting, much attention has been given to achieving maximum brilliancy of the gem. Best results are usually obtained by designing the setting so that light will be admitted underneath the sides of the diamond. This has been accomplished with the well known "prong" settings in which the stone is supported in a somewhat elevated position by means of spaced prongs rising from the surface of the ring or other article of jewelry. Considerable attention has been given as well to the designing of settings with view to achieving an appearance of size, it being desirable that the diamond be made to look as large as possible. For this purpose, the so-called "flat top" settings have been quite generally used. The diamond, with such a setting, appears against a more or less solid back-ground of "white" metal, or other suitably colored metal, the outline of the ground substantially conforming with the general contour of the stone so that to a certain extent the stone appears to assume the size of the background which is larger than the stone itself. The illusion is rather imperfect however, and this type of mounting generally detracts from the brilliancy of the stone.

It is an object of my invention to provide a setting which combines the principal advantages of the two types of settings I have described, while avoiding the artificiality of the ordinary flat top setting, so as to obtain a brilliancy partaken of by both the stone and its setting in such a way as to create an impression of greater size which can be dispelled only upon a very minute inspection and study.

A further object is to provide a setting which permits the framing of the stones with a considerable amount of metal without detracting unduly from the effect of the diamond and with retention of maximum brilliancy.

Another object is to provide an improved setting which is simple and inexpensive to construct, and yet which gives more effectiveness to the stones.

A particular object of the invention is to provide a setting which magnifies the size of a series of small stones more effectively than settings previously known to the art.

Other objects and advantages will appear as the description proceeds. In the drawing, which depicts a number of illustrative embodiments of the invention:

Fig. 1 is a plan view of a wedding ring setting employing a series of small diamonds. Fig. 2 is a longitudinal sectional view taken on the line 2—2 of Fig. 1; Fig. 3 a transverse sectional view taken on the line 3—3 of Fig. 1; and Fig. 4 a detail elevational view taken as indicated at 4—4 of Fig. 1.

Figs. 5, 6, 7 and 8 are plan views illustrating a number of other embodiments of the setting as they appear before the stones have been set and the mill-graining performed. The settings shown in these views represent metal inserts suitable for application to a wedding ring such as shown in part in Figs. 1 to 4.

In accordance with my invention the stones are set in or slightly above a metal background, or frame, the general contour of which conforms or substantially conforms in shape to the general contour of the stones as viewed from above, yet which is so constructed as to admit the proper amount of light at the lower sides of the stones. The arrangement is such that the mounting partakes of something of the brilliancy of the stones, creating an unusually effective impression that the stones are larger than they are shown to be by measurement or by closer scrutiny. The geometrical configuration of the setting together with the manner of admitting the light apparently cooperate in some peculiar manner to produce this impression in which the brilliancy of the stone to a certain extent seems to project itself to the edges of its metal "frame". In the case of a round diamond this effect can be achieved for example with a round setting or frame, or with a setting substantially conforming to the contour of the gem such as a hexagonal setting of the particular form to be described. It cannot be achieved in any substantial degree with a square setting, or with settings of other contours that do not also possess the features which will now be set forth with reference to the particular embodiments shown in the drawing.

Referring first to the embodiment illustrated in Figs. 1 to 4 inclusive, I have shown my invention as applied to a setting for a diamond wedding ring, in which a plurality of small diamonds are employed. The ring 10 is provided with a suitable recess 11 in its outer periphery to receive a metal insert or overlay 12 into which the diamonds 13 are set. The insert 12 preferably is formed of a metal whose color blends with that

of the stone. In a diamond setting as shown, this insert should be made of one of the so-called "white" metals, such as white gold or platinum. It will be understood that if the ring 10 itself is 5 made of such a white metal, it is not necessary to employ a separate insert and the diamonds can be mounted directly in the ring. I consider it preferable, however, to employ the separate insert. 10 The diamonds 13 are cut in the usual manner. The diamonds shown are of the form known in the art as "round" diamonds as distinguished, for example, from square or oblong diamonds. 15 Fig. 5 shows the form of the insert or overlay 12 before the setting has been made. It may be constructed by known metal-working operations so as to provide a plurality of adjoining octagonal portions 14. The upper face of the member 12 is substantially flat in the transverse direction and is of arcuate form longitudinally, conforming in general to the shape of the ring to which it is to be applied. The member 12 is provided with a series of apertures 15 located substantially at the centers of the contiguous 20 octagonal segments 14. The upper face of the member is provided with a longitudinal groove 16 intersecting the apertures 15, and with transverse grooves 17 intersecting the longitudinal groove at substantially right angles and at substantially 25 the centers of the apertures 15.

The body of the ring 10 is provided with apertures 18' which are arranged in alignment with the apertures in the insert. The apertures 15 and 18' may be formed separately in the two 30 members or may be formed as a single operation after the ring and insert have been assembled. Assuming that the insert 11 is in place in the ring 10, but is still in the form shown in Fig. 5, the setting of the diamonds will now be described. First, however, it may be observed that the longitudinal groove 16 of the insert is 35 preferably projected through the ends of the recess 11, as at 18, so as to blend into the surface of the ring. The diamonds 13 are now set in accordance with the usual practice, the apertures 40 15 being cut by the setter to receive the diamonds, and the metal of the face of the insert 12 being peened or "beaded" over the edges of the diamonds in the desired manner. The 45 working of the metal of the face of the insert is performed in such a manner as to leave projecting flanges or raised portions 19 (Fig. 4) around the periphery of the octagonal segments 14. As will be seen from Fig. 1, these raised portions 50 extend between the ends of the grooves 17 and the sides of the groove 16. The flanges or raised portions 19 finally are mill-grained in any suitable manner known to the art of diamond setting so as to form what might be described as a 55 beaded or serrated edge 20.

It will be observed that the diamonds 13 have a round girdle and octagonal table so that the edges of the metallic member 12 may be said to 60 substantially conform in shape or configuration to the contour of the stones. The upper face of the member thus provides a frame for the stones, but the grooves 16 and 17 project through the edges of the frame, intersecting at substantially right angles at substantially the center of the stones. In the construction I have illustrated, the grooves do not destroy the symmetry of the frame yet they admit sufficient light at the 65 lower sides of the stones to give the desired brilliancy. The arrangement is such that the brilliancy of the stones appears to be imparted to the

metallic frame in such a way as to create the impression that the stones are more nearly of the same size as their frames.

In Figs. 6, 7 and 8 I have illustrated modified forms of inserts. In the embodiment of Fig. 6 5 the longitudinal groove 21 corresponds to the groove 16 of the insert shown in Fig. 5, and the transverse grooves 22 to the grooves 17 of that insert. The grooves 21 and 22 intersect at the centers of the apertures 24. In this embodiment, 10 however, the sides of the insert are beveled at 23 adjacent the ends of the transverse grooves 22. It will be observed that in this form the apertures 24 are spaced somewhat closer together than is the case with the embodiment previously described, so that the center-to-center distance of the apertures is somewhat less than the transverse dimension of the insert, i. e., than the width of the insert. This brings the stones closer together so that there is somewhat less metal between them and therefore greater mass brilliancy. 15

The insert shown in Fig. 7 is constructed to provide intersecting circular segments 25, the apertures 26 being so spaced that the points of 20 intersection of the segments fall a substantial distance away from the longitudinal center line of the insert. The face of the insert is provided with intersecting, transverse grooves 27 and 28 in a manner similar to that which has been described with reference to the other embodiments. 25

A still further embodiment is illustrated in Fig. 8, in which the insert is provided not only with longitudinal and transverse grooves 29 and 30, respectively, intersecting at substantially the center of the apertures 31, but also with transverse grooves 32 located approximately midway between the centers of the apertures. The grooves 32 preferably are deeper than the grooves 30 and their ends are beveled downwardly toward the 35 outside as at 33. The longitudinal, upper edges of the insert are beveled, as at 34, being intersected by the ends of the grooves 30 and by the beveled portions 33 of the grooves 32. The effect of the construction when employed as a setting for a series of small diamonds is to create 40 an impression of increased size of the gems while giving improved brilliancy to the ensemble. Considering each unit of the setting, it will be observed that the setting is greater in dimension 45 transversely of the insert than longitudinally thereof or circumferentially of the ring. 50

While I have described my invention primarily as applied to multiple settings, it will be understood that it is applicable also to the setting 55 of single stones. This is true, for example, of the form of setting illustrated particularly in Figs. 1 to 4. The multiple settings can be used for the small side stones of a mounting. The multiple settings also can be modified to bring 60 the stones even closer together so that the adjacent edges come together or approach this condition, it being essential in every case, however, that the contour of the metallic frame simulates the contour of the diamonds and that the grooves 65 be provided in the manner I have described so as to intersect substantially the centers of the diamonds. When the multiple settings are so modified as to bring the stones close enough together that the adjacent edges come together or 70 approach this condition, it may be desired to omit the longitudinal groove, and this can be done while retaining certain important advantages of my invention. Again it may be desired to have the longitudinal groove at only the ends of 75

the series of stones, inasmuch as a longitudinal groove between the stones would largely be obscured by the stones. It will also be understood that other forms and contours may be employed 5 for the inserts. For example, they might be of generally hexagonal form instead of the octagonal form shown in Fig. 5. The invention is not limited with respect to the number of stones employed in the series settings. For example, five 10 or more stones may be employed. Other possible modifications will suggest themselves to those skilled in the art to which this invention pertains and I do not wish to be limited to the specific forms illustrated. The terms and expressions 15 which I have employed are used as terms of description and not of limitation.

I claim:

1. A setting for precious stones comprising a metallic member of a color blending with the 20 stone, said member presenting an upper face having a contour substantially conforming in shape to the contour of the stone, means for retaining the stone in position to be framed by said upper face, and a plurality of grooves in said face intersecting at substantially right angles at substantially the center of the stone, said grooves admitting light so as to enhance the blending of the stone with the setting. 25

2. A setting for precious stones comprising a metallic member of a color blending with the 30 stone, said member presenting an upper face having a contour substantially conforming in shape to the contour of the stone, means for retaining the stone in position to be framed by said upper face, and a pair of grooves in said face, one of 35 said grooves extending transversely of the setting and the other longitudinally thereof, said grooves admitting light so that the brilliancy of the stone is projected to the frame formed by said upper 40 face.

3. A setting for a plurality of precious stones comprising a metallic member of a color blending with the stones, said member presenting an upper face having contours substantially conforming in shape to the contours of the stones, means for retaining the stones in position to be framed by said upper face, a longitudinal groove intersecting substantially the centers of the positions of the stones, and transverse grooves intersecting substantially said centers, said grooves admitting light so as to enhance the blending of the stones with the setting. 50

4. A setting for round diamonds comprising a metallic member of a color blending with the diamond, said member presenting an upper face having an octagonal contour, means for retaining the diamond in position to be framed by said upper face, and a plurality of grooves in said 55 face intersecting at substantially right angles at substantially the center of said contour.

5. A setting for round diamonds comprising a metallic member of a color blending with the diamond, said member presenting an upper face having an octagonal contour, means for retaining the diamond in position to be framed by said upper face, and a pair of grooves in said 60 face, one of said grooves extending transversely of the setting and the other longitudinally thereof.

6. A setting for a plurality of round diamonds comprising a metallic member of a color blending with the diamonds, said member presenting an upper face having a contour conforming to a series of octagons placed in a row, means for

retaining the diamonds in position to be framed by said upper face, a longitudinal groove intersecting substantially the centers of the octagons, and transverse grooves intersecting substantially said centers. 5

7. A setting for round diamonds comprising a metallic member of a color blending with the diamond, said member presenting an upper face of substantially circular shape, means for retaining the diamond in position to be framed by 10 said upper face, and a plurality of grooves in said face intersecting at substantially right angles at substantially the center of said contour. 15

8. A setting for a plurality of round diamonds comprising a metallic member of a color blending with the diamonds, said member presenting an upper face having a contour conforming to a series of circles, means for retaining the stones in position to be framed by said upper face, a longitudinal groove intersecting substantially the 20 centers of the circles and transverse grooves intersecting substantially said centers. 25

9. A setting for a plurality of round diamonds comprising a metallic member of a color blending with the diamonds, said member presenting an upper face having a contour conforming to a series of intersecting circles, means for retaining the stones in position to be framed by said upper face, a longitudinal groove intersecting substantially the centers of the circles and trans- 30 verse grooves intersecting substantially said centers.

10. A setting for a plurality of precious stones comprising a metallic member of a color blending with the stones, said member presenting an upper face having contours conforming substantially in shape to the contours of the stones, means for retaining the stones in position to be framed by said upper face, a longitudinal groove intersecting substantially the centers of the positions of the stones, and transverse grooves intersecting substantially said centers, said centers being spaced apart by a distance which is less than the transverse width of said upper face. 35

11. A setting for a plurality of precious stones comprising a metallic member presenting an upper face having contours substantially conforming in shape to the contours of the stones, means for retaining the stones in position to be framed by said upper face, a longitudinal groove intersecting substantially the centers of the positions of the stones, and transverse grooves intersecting substantially said centers, the framing portions of said upper face which forms the setting for each of the plurality of stones being of greater dimensions transversely of the setting than longitudinally thereof. 40

12. A diamond-set ring comprising a setting portion presenting an upper face having contours substantially conforming in shape to the contours of the diamonds, means for retaining the diamonds in position to be framed by said upper face, a longitudinal groove intersecting substantially the axis of the diamonds and transverse 50 grooves intersecting substantially said axis. 55

13. A diamond-set ring comprising a setting portion presenting an upper face having contours substantially conforming in shape to the contours of the diamonds, means for retaining the diamonds in position to be framed by said upper face, a longitudinal groove intersecting substantially the axis of the diamonds and transverse grooves intersecting substantially said axis, said upper face being of greater dimension trans- 60

versely of the ring than the circumferential distance between the axis of the diamonds in the plane of said upper face.

14. A setting for a plurality of precious stones comprising a metallic member of a color blending with the stones, said member presenting an upper face having contours substantially conforming

in shape to the contours of the stones, means for retaining the stones in position to be framed by said upper face, and transverse grooves intersecting substantially the centers of the positions of the stones.

LEE HIRSCH.
